BATCHING MACHINE

Milton O. Haeger, La Grange Park, Ill., assignor
to Abell-Howe Company, Chicago, Ill., a corpora-
tion of Illinois

Application March 8, 1949, Serial No. 80,214

7 Claims. (Cl. 222—135)

1

This invention relates to machines for use in the production of concrete and analogous mixes, and has to do with a batching machine for accurately measuring certain of the ingredients of the desired mix.

It is known to provide machines having means for measuring the ingredients of the desired mix. Such known machines are, in general, in the form of central or stationary plants including, as a permanent part thereof, a concrete mixer, and are of quite heavy construction, frequently quite complicated and often quite expensive. To my knowledge, none of the known machines is suitable for use with a separate concrete mixer having a charging skip for reception of the ingredients or materials to be mixed.

It is of importance that the ingredients of a concrete mix be accurately proportioned, to assure maximum strength and efficiency for its intended use of the resultant concrete. Portable concrete mixers, having a charging skip which receives the ingredients of the mix and discharges them into the mixer, are extensively used. In using mixers of this type, the common practice is to throw into the skip a certain number of shovelfuls of fine aggregate such as sand, and a certain number of shovelfuls of coarse aggregate, such as crushed stone or gravel, the number of shovelfuls of each depending upon the desired mix. Obviously, that method is inaccurate and the batches of concrete mix may vary considerably as to proportions of fine and coarse aggregates. Even assuming that the workmen keep accurate count of the number of shovelfuls of sand and gravel, for example, which they throw into the skip, the amount of material in one shovelful will vary from that in another shovelful, and if the workman becomes tired or lazy the variation increases. There is also the possibility that the workman may not count the shovelfuls correctly, which is not uncommon and aggravates the situation. The cement used in making concrete commonly comes in bags each containing an accurately measured amount, and presents no difficulty. Also, the water used in the mix can readily be accurately measured in a container commonly provided for that purpose and presents no problem. The main difficulty in the use of portable concrete mixers is the inability to proportion accurately the fine and coarse aggregates, as and for the reasons above noted.

My invention is directed to a machine of comparatively simple and inexpensive construction and light weight, which will measure accurately

the aggregates used in concrete mixes and is suited for use with a portable concrete mixer having a skip or equivalent charging means. To that end I provide a batching machine which may readily be transported to the site where the mixer is to be used and which delivers the aggregates in accurately measured amounts or batches to the skip of the mixer as required. More particularly, I provide measuring hoppers movable to an inner charging position in the machine, in which each of them receives a predetermined amount of aggregate, and to an outer discharging position overlying the skip of the mixer, into which the contents of the hoppers are discharged. The hoppers are automatically discharged when they reach discharging position and are automatically recharged when they return to charging position. That assures that there will always be the proper amounts of aggregates in the skip of the mixer prior to the end of a mixing operation, which avoids objectionable delay and is conducive to high output of the mixer. Further objects and advantages of my invention will appear from the detail description.

In the drawings:

Figure 1 is a side view of a batching machine embodying my invention, with the measuring hoppers in their inner positions;

Figure 2 is a fragmentary side view of the machine of Figure 1, as seen from the opposite side, showing the operating control means including the main control switch and the limit switches and associated parts;

Figure 3 is a fragmentary front view, on an enlarged scale, of the machine of Figure 1, showing the lower portion of the storage bin, the carriage supporting frames and the carriages thereon and associated parts, with one of the measuring hoppers partly broken away and shown in section;

Figure 4 is a side view of one of the carriage supporting frames and the carriage thereon and associated parts, the carriage being shown in full lines in its forward or outer position and indicated, in dotted lines, in its rearward or inner position, the carriage supporting frame being in part broken away;

Figure 5 is a sectional view, on an enlarged scale, taken substantially on line 5—5 of Figure 1, certain parts being broken away and certain other parts being omitted for clearness of illustration;

Figure 6 is a sectional view, on an enlarged scale, taken substantially on line 6—6 of Figure 3,

certain parts being broken away and the carriage supporting frame being in part shown in side view;

Figure 7 is a plan view of one of the carriage supporting frames, partly broken away and in part broken away and shown in section;

Figure 8 is a plan view of one of the carriages; and

Figure 9 is a sectional view, on an enlarged scale, taken substantially on line 9—9 of Figure 8.

As above indicated, the batching machine of my invention is particularly suited for use with a concrete mixing machine and I shall describe it as so used, it being understood, however, that the machine of my invention, in its broader aspects, may be used for measuring various materials which are to be used in various mixes or for other purposes. The batching machine of my invention comprises a suitably formed storage bin 10 comprising an upper portion 11 which is rectangular shape in plan and a lower downwardly tapering portion 12 provided, at its mid-width, with an upwardly extending inverted V-shaped recess 13 extending from front to back thereof. The bin 10 is divided interiorly, by a partition 14 extending from front to back thereof, into two compartments 15 and 16, the partition extending upward from the apex of the recess 13. The storage bin 10 is suitably mounted and secured in a suitably constructed and braced frame 17 constituting therewith a unitary structure. The partition 14 extends upward above the bin 10 and is provided at its central portion with a reinforcing structure or lifting pad 18 having an opening therein for reception of a hook of a crane or like means, whereby the structure including the bin and the frame and the parts carried thereby may be lifted as a unit and placed upon a float by which it is transported to the site of operations.

Each of the compartments 15 and 16 is provided with a depending neck 19 which is of rectangular-approximately square-shape in plan and defines a discharge opening leading from that compartment. The neck 19 fits snugly between channel side members 20, shown more clearly in Figures 5 and 7, and channel cross-members 21, extending between and secured to the members 20, of a carriage supporting frame 22. The frame 22 further comprises end channel members 23 extending between and suitably secured to the side members 20. The side members 20 and the cross members 21 are bolted or otherwise suitably secured to neck 19, and the side members 20 of frame 22 are also bolted or otherwise secured to an angle cross member 24 of frame 17 at the back thereof. The frame 22 is thus supported by neck 19 of compartment 15 of the storage bin 10, and by the angle cross member 24. There are two frames 22 each constructed and mounted in the manner described, these two frames being disposed adjacent each other in spaced parallel relation.

Each of the frames 22 supports a carriage 26 of elongated rectangular or oblong shape in plan, shown more clearly in Figures 5 and 8. The carriage 26 comprises channel side members 27 connected by forward and rearward yokes 28 suitably secured thereto, one of the yokes 28 being disposed at the rearward end of carriage 26 and the other yoke 28 being disposed a substantial distance from the forward end of carriage 26. A lower plate 29 extends between the side members 27 of the carriage frame in underlying rela-

tion thereto, and is welded or otherwise suitably secured thereto. An upper plate 30 (Figures 5 and 6) seats upon plate 29, to which it is welded or otherwise suitably secured, and extends between the side members 27 with its side edges in close proximity thereto. The plates 29 and 30 extend the full length of carriage 26 and are provided, adjacent the forward end thereof, with a charging opening comprising a substantially semi-circular forward portion 31 and a substantially V-shaped rearward portion 32 which subtends the forward portion 31, as is shown more clearly in Figure 8. The opening through plate 29 extends rearward beyond the opening through plate 30 (Figure 9) and the edge of plate 30 defining portion 32 of the charging opening is beveled upward and forward at 33. That provides a cutting edge and inclined or beveled surface extending therefrom which will readily pass through a column of aggregate extending through the charging opening, as will be explained more fully later.

The carriage 26 is provided, at each side thereof, with two flanged wheels 35 mounted at the inner face of side members 27, which are spaced outward from the side channels 29 of frame 22, which the carriage straddles. The wheels 35 travel on the lower flanges of channel members 20, which thus serve as tracks for the carriage 26. Angle strips 36 are welded or otherwise suitably secured to the other outer faces of the channels 20 of frame 22, with their upper flanges overlying the wheels 35 in proximity thereto, effective for restraining the wheels and the carriage against upward movement. That guards against binding due to tilting of the carriage. The upper face of plate 30 is disposed in close proximity to a rectangular wear frame 38 bolted or otherwise suitably secured to the underfaces of the side members 20 and cross members 21 of the carriage supporting frame 22. It will be clear, from what has been said, that the members 20 and 21 define an outlet opening 39 leading downward from neck 19, and the frame 38 defines an opening 40 in close proximity to the upper face of plate 30.

A channel member 42 is welded or otherwise suitably secured to brackets 43 (Figures 5, 6 and 8), which are welded or otherwise suitably secured to the underface of plate 29. This channel member 42 is disposed midway between the side members 27 of the carriage and extends lengthwise of the latter, preferably from the rearward yoke 28 to the forward yoke. There are, of course, two carriages 26, both constructed in the manner above described, each provided with a channel member 42 disposed as stated. A rack bar 44 is welded or otherwise suitably secured to the channel member 42 and meshes with a spur pinion 45 fixed on a drive shaft 46 rotatably mounted in suitably disposed bearing blocks 48 carried by an angle cross member 49 of frame 17, the outer end of shaft 46 being mounted in a bearing block 15 carried by a bracket structure 51 suitably secured to frame 17. From what has been said, it will be clear that when shaft 46 is rotated in one direction the carriages 26 are moved forwardly toward the front of the frame 17, and when the shaft 46 is rotated in the opposite direction the carriages are moved inward or toward the rear of frame 17.

A spur gear 53 is fixed on shaft 46 adjacent the outer end thereof and meshes with a spur pinion 54 of a speed reducing unit 55, of suitable known type, appropriately mounted on the frame

17. The unit 55 is driven by an electric motor 56 appropriately mounted on frame 17, through a V-belt 57 passing about the V-pulleys 58 and 59 respectively secured on the shaft of motor 56 and the driven shaft of unit 55. Within the broader aspects of my invention, the shaft 46 may be driven by any suitable reversible driving means.

A panel 62 is suitably mounted on frame 17 at one side and adjacent the front thereof. This panel carries a time relay 63, a reversing controller 64, a main control switch 65 and a safety switch 66, all of suitable known type. A suitable voltage transformer 67 may also be mounted on the panel 62, where required. A power line receptacle 68 is provided for establishing, through a suitable electrical cable, connection between the controller 64 and a suitable source of electrical energy at the site of operations. Two limit switches 69 and 70 are mounted above the carriage 26, switch 69 being adjacent the front of frame 17 and switch 70 being a substantial distance in rear of switch 69. Each of the switches 69 and 70 is provided with a downwardly extending operating arm 71 carrying at its lower end a roller 72. This roller 72 is disposed for contact by a trip plate 73 mounted on the carriage 26. It will be understood, of course, that appropriate electrical connections are provided between the controller 64, relay 63, switch 65, the transformer 67, when used, and the switches 69 and 70.

When the carriage 26 is in its inner or rearward position shown in Figure 2, the trip plate 73 is in contact with roller 72 of the arm 71 of switch 70, effective for maintaining that switch open. At that time, the switch 69 is closed and the motor 56 is conditioned for driving the shaft 46 in clockwise direction as viewed in Figure 1, but the circuit of motor 56 is then opened through the control switch 65. This latter switch is a push button type of switch and when button 74 thereof is pressed it is effective for closing the circuit of motor 56 through the controller 64 and the limit switch 69. The carriage 26 is then moved from its inner or rearward position to its full forward position indicated in dotted lines in Figures 1 and 2. As carriage 26 reaches its latter position, trip plate 73 opens the limit switch 69. Opening of switch 69 is effective for reversing the motor 56 and stopping it for a short period of time predetermined by the relay 63. At the end of the predetermined time, the circuit of motor 56 is closed, by the relay 63, through the controller 64 and the limit switch 70, it being understood that this latter switch closes during the first part of the forward travel of carriage 26 and remains closed until the carriage is returned to its inner or rearward position. When the motor circuit is closed by the relay 63, the motor 56, the field windings of which have been reversed as above described, drives the shaft 46 in counter-clockwise direction, as viewed in Figure 1, thus returning the carriage 26 to its inner or rearward position, the trip plate 73 opening limit switch 70 as the carriage reaches that position. That opens the circuit of motor 56, completing one cycle of operation. Pressing button 74 of control circuit 65 initiates a succeeding cycle, as will be clear. It will be seen, from what has been said, that by pressing button 74 of control switch 65, the carriage 26 is caused to move from its rearward position to its full forward position, remains in its full forward position for a time predetermined by the setting of the time relay 63, and is then returned to its inner or rear-

ward position, in which it remains until the button 74 is again pressed, the operation throughout a complete cycle being entirely automatic.

Each of the carriages 26 is provided, at the forward portion thereof, with a depending measuring or batching hopper. The batching hopper 76 for the coarse aggregate, such as crushed stone or gravel, comprises an upper section in the form of a sleeve 77 which is rectangular in plan, underlies the forward portion of plate 29 of carriage 26 (Figures 3, 6 and 8) and is secured thereto by corner plates 78 welded to sleeve 77 and bolted or otherwise suitably secured to plates 29 and 30 of the carriage. Angle strips 80 are fixed to the sides of sleeve 77 and each of these strips receives two screw rods 81 suitably secured therethrough. The hopper 76 is of telescopic construction and further comprises a main section or body 82 fitting over and slidably on the sleeve 77. Angle strips 83 are fixed to the sides of body 82 and each of the strips 83 has secured therethrough two screw rods 84 disposed coaxially with the respective rods 81. The rods 81 and 84 are connected by a turnbuckle 85, by means of which the main portion or body 82 of the hopper 76 may be adjusted relative to sleeve 77 for varying the effective capacity of hopper 76, as will be readily understood. Conveniently, the front wall of sleeve 77 is provided with an appropriate scale, shown more clearly in Figure 3, for indicating the effective capacity in cubic feet of the hopper 76 for the respective adjustments thereof.

The body 82 of hopper 76 is reduced at its lower portion 86, this reduced lower portion 86 being of rectangular cross section with its inner side wall in the plane of the inner side wall of body 82 and its outer side wall connected to the outer side wall of body 82 by a downwardly inclined wall 87. The lower end of reduced portion 86 of body 82 of the hopper 76 is closed by a gate 88. This gate 88 comprises two arms 89 pivoted on a pintle rod 90 extending through two straps 91 fixed to the sides of reduced portion 86 of the hopper body 82 and extending therebelow. The rear wall 93 of reduced portion 86 of hopper body 82 is inclined downward and forward, as shown more clearly in Figure 4, for a purpose which will be explained more fully presently.

The arms 89 extend rearward a substantial distance beyond the pintle rod 90 and are connected, at their rearward ends, by a cross angle member 95. The arms 89 are further connected, a short distance in rear of pintle rod 90, by a cross member 96. A suitable number of counter weights 97 are suitably mounted, conveniently by bolting, on the angle cross member 95. A closure plate 98 is suitably secured, conveniently by welding, on the upper edges of the forward portions of the arms 89, this plate being of adequate area to close the lower end of the hopper when in its fully raised or operative position.

A wear bar 100 is secured, conveniently by welding, to the underface of closure plate 98 at the forward edge thereof. When plate 98 is in its raised operative position, closing the lower end of the hopper, the bar 100 is engaged by bill 101 of a latch arm 102 fixed on a stub shaft 103 rockably mounted, at the front of hopper 76, in brackets 104 and 105 welded or otherwise suitably secured to hopper 76. The brackets 105 are disposed in close proximity to the sides of latch arm 102 and, in cooperation therewith, restrain the shaft 103 against endwise movement. An upwardly extending angle arm 106 is fixed on the outer end of shaft 103. A flexible trip member

or cable 107, including a turnbuckle 108, is anchored at one end to the upper end of arm 106 and, at its other end, to cross member 49 of frame 17. The effective length of trip member 107 is such that the arm 106 is swung in counter-clockwise direction, as viewed in Figure 4, effective for swinging the latch arm 102 in like direction to its inoperative or releasing position, when the carriage 26 reaches its outermost or discharging position. The other carriage 26 carries, at its forward end portion, a hopper 109 for measuring batches of sand or other fine aggregate. The hopper 109 is somewhat smaller than hopper 76 but is constructed and mounted in the same manner as the latter hopper and is provided, at its lower end, with a gate 88 and associated latch and trip means the same as the gate and the latch and trip means of the hopper 76. Accordingly, no further description of the hopper 109 and associated parts is necessary. Preferably, the gate 88 for hopper 76 is provided, at each side thereof, with an upwardly extending triangular plate 110 welded or otherwise suitably secured to the plate 98, which may be extended beyond the arms 89 for that purpose. The plates 110 are disposed in close proximity to the side walls of the reduced portion 86 of hopper body 82, when the gate is in its closed position, effective for preventing twisting or side thrust of the gate. Likewise, the gate 88 for the hopper 109 may be provided with side plates or wings 110, though ordinarily that is not necessary.

It will be clear, from what has been said, that the two carriages 26 are operated in like manner and to like extent by rotation of the shaft 46 in appropriate direction. When the carriages 26 are in their inner or rearward positions, the opening 31—32 of each carriage is disposed in underlying relation to the opening 40 defined by the wear frame 38. The aggregate from the corresponding compartment of the storage bin 12 then flows into the hopper, completely filling it, there being a column of material or aggregate extending from the hopper upward into the compartment of the bin, as will be understood. In practice, the concrete mixer is disposed adjacent the front of frame 17, with skip 112 extending rearwardly a short distance between the two front uprights of the frame, as in Figure 1. The control switch 65 is disposed adjacent the front of frame 17, so as to be readily accessible to the attendant or operator of the mixer. When the button 74 of switch 65 is pressed, the carriages 26 are moved to their forward discharging positions, in which the measuring hoppers 76 and 109 are disposed outward beyond the frame 17, as in Figure 4, and in overlying relation to the skip 112, as indicated in Figure 1. When the hoppers reach that position, the latch arms 102 are tripped by the members 107 and the gates 88 are then swung downward into open position by the weight of the material within the hoppers. In that manner, the aggregates are discharged from the hoppers into the skip 112, and are delivered by the latter to the mixer, it being understood that a proper amount of cement is also placed in the skip and that a proper amount of water is added preliminary to, or during, the mixing operation. The carriages 26 remain in their forward discharging positions for a short length of time, predetermined by the setting of the time relay 63, sufficient to assure that the aggregates will be completely discharged from the measuring hoppers. That is desirable in the event the aggregates are moist to such an extent

as to retard discharge thereof from the measuring hoppers, while also providing an opportunity for bumping the hoppers to assure complete discharge thereof, if necessary. At the end of the period predetermined by the time relay, the carriages are returned to their rearward or inner positions, at which time the gates 88 have been swung to closed position by the counterweights 97, and latched in such position by the latch arms 102. In that connection, when the gate 88 is released, as the carriage 26 reaches its outer or discharging position, it is swung downward by the weight of the material within the hopper, as has been explained. When the gate 88 is thus moved to its fully opened position, the angle cross member 95 strikes a bar 112, which serves as a bumper, secured to back wall 93 of the reduced portion 86 of body 82 of the hopper 76, or of the hopper 109, as the case may be.

As the carriages 26 move from their inner or rearward positions to their outer or forward positions, the plates 30 of the carriages move across the wear frames 38 and part the column of material extending therethrough. In that connection, the beveled edge 33 of plate 30 provides a cutting element which readily severs the column of material and reduces likelihood of aggregate jamming between the wear frame 38 and the edge 33 of plate 30, it being noted that the wear frame 38 projects inward a short distance beyond the members 20 and 21. That, in conjunction with the beveled edge 33, permits of ready displacement either upward or downward of particles or pieces of aggregate which might otherwise tend to become jammed between wear frame 38 and the edge 33 of plate 30, thereby guarding against such jamming. In the forward or outward movement of the carriages 26, the plates 30 serve as valves for closing the openings 40 defined by the wear frames 38, as will be understood from Figure 5, in which the carriages 26 are shown in their outer or discharging position. Upon return of the carriages 26 to their inner or rearward position, the measuring hoppers are recharged in the manner previously described. It will be understood that when a measuring hopper is discharged, the gate 88 thereof is returned to closed position by the counterweights 97, in which position it is latched by the latch arm 102, in the manner previously described.

As above indicated, changes in detail may be resorted to without departing from the field and scope of my invention, and I intend to include all such variations, as fall within the scope of the appended claims, in this application in which the preferred form only of my invention has been disclosed.

I claim:

1. In a batching machine for delivering fine and coarse aggregates separately and in measured quantities to a skip of a concrete mixer, a supporting frame, a two compartment bin structure on said frame provided at its lower end with two juxtaposed discharge necks respectively opening downward from said compartments, two parallel carriages mounted on said frame respectively underlying said necks and movable transversely of said frame to an outer discharging position projecting beyond said frame and an inner charging position, batching hoppers depending from said carriages disposed outward beyond said frame in the discharging position of said carriages, releasable gates normally closing the lower ends of said hoppers, means controlled

by said carriages for delivering materials from said bin compartments to said hoppers when said carriages are in charging position and cutting off delivery of materials from said bin compartments in all other positions of said carriages, means for similarly and simultaneously moving said carriages to said outer position and to said inner position, and means for releasing said gates for opening as said carriages reach discharging position.

2. In a batching machine for delivering fine and coarse aggregates separately and in measured quantities to a skip of a concrete mixer, a supporting frame, a two compartment bin structure on said frame provided at its lower end with two juxtaposed discharge necks respectively opening downward from said compartments, two parallel carriages mounted on said frame respectively underlying said necks and movable transversely of said frame to an outer discharging position projecting beyond said frame and an inner charging position, batching hoppers depending from said carriages disposed outward beyond said frame in the discharging position of said carriages, the lower portion of each hopper being of materially less cross section than the upper portion thereof and offset relative to said upper portion toward the other hopper, releasable gates normally closing the lower ends of said hoppers, means controlled by said carriages for delivering materials from said bin compartments to said hoppers when said carriages are in charging position and cutting off delivery of materials from said bin compartments in all other positions of said carriage, means for similarly and simultaneously moving said carriages to said outer position and to said inner position, and means for releasing said gates for opening as said carriages reach discharging position.

3. In a batching machine for delivering fine and coarse aggregates separately and in measured quantities to a skip of a concrete mixer, a supporting frame, a two compartment bin structure on said frame provided at its lower end with two juxtaposed discharge necks respectively opening downward from said compartments, two parallel carriages mounted on said frame respectively underlying said necks and movable transversely of said frame to an outer discharging position projecting beyond said frame and an inner charging position, batching hoppers depending from said carriages disposed outward beyond said frame in the discharging position of said carriages, said hoppers being of substantially rectangular cross section and each having its lower portion materially reduced in width relative to its upper portion, the inner side wall of the reduced lower portion of each hopper being substantially in the plane of the inner side wall of the upper portion and the outer side wall of the reduced lower portion being connected to the outer side wall of the upper portion by a downwardly and inwardly inclined wall, releasable gates normally closing the lower ends of said hoppers, means controlled by said carriages for delivering materials from said bin compartments to said hoppers when said carriages are in charging position and cutting off delivery of materials from said bin compartments in all other positions of said carriages, means for similarly and simultaneously moving said carriages to said outer position and to said inner position, and means for releasing said gates for opening as said carriages reach discharging position.

4. In a batching machine for delivering fine 75 two juxtaposed discharge necks respectively open-

and coarse aggregates separately and in measured quantities to a skip of a concrete mixer, a supporting frame, a two compartment bin structure on said frame provided at its lower end with two juxtaposed discharge necks respectively opening downward from said compartments, two parallel carriages mounted on said frame respectively underlying said necks and movable transversely of said frame to an outer discharging position projecting beyond said frame and an inner charging position, batching hoppers depending from said carriages disposed outward beyond said frame in the discharging position of said carriages, said hoppers being of substantially rectangular cross section and each having its lower portion materially reduced in width and length relative to its upper portion, the inner side wall of the reduced lower portion of each hopper being substantially in the plane of the inner side wall of the upper portion, the outer side wall of the lower reduced portion being connected to the outer side wall of the upper portion by a downwardly and inwardly inclined wall and the rear wall of said lower portion being inclined downwardly and forwardly from the rear wall of the upper portion, releasable gates normally closing the lower ends of said hoppers, means controlled by said carriages for delivering materials from said bin compartments to said hoppers when said carriages are in charging position and cutting off delivery of materials from said bin compartments in all other positions of said carriages, means for similarly and simultaneously moving said carriages to said outer position and to said inner position, and means for releasing said gates for opening as said carriages reach discharging position.

5. In a batching machine for delivering fine and coarse aggregates separately and in measured quantities to a skip of a concrete mixer, a supporting frame, a two compartment bin structure on said frame provided at its lower end with two juxtaposed discharge necks respectively opening downward from said compartments, two parallel carriages mounted on said frame respectively underlying said necks and movable transversely of said frame to an outer discharging position projecting beyond said frame and an inner charging position, batching hoppers depending from said carriages disposed outward beyond said frame in the discharging position of said carriages, said hoppers being of substantially rectangular cross section and each having its lower portion materially reduced in width relative to its upper portion, the inner side wall of the reduced lower portion of each hopper being substantially in the plane of the inner side wall of the upper portion and the outer side wall of the reduced lower portion being connected to the outer side wall of the upper portion by a downwardly and inwardly inclined wall, closure gates pivoted on the lower ends of said hoppers at the rear thereof, latch means effective for positively holding said gates closed, means for releasing said latch means and thereby releasing said gates for opening as said carriages reach discharging position, and means for limiting the extent of opening of said gates and returning them to closed position.

6. In a batching machine for delivering fine and coarse aggregates separately and in measured quantities to a skip of a concrete mixer, a supporting frame, a two compartment bin structure on said frame provided at its lower end with two juxtaposed discharge necks respectively open-

ing downward from said compartments, two parallel carriages mounted on said frame respectively underlying said necks and movable transversely of said frame to an outer discharging position projecting beyond said frame and an inner charging position, batching hoppers depending from said carriages disposed outward beyond said frame in the discharging position of said carriages, said hoppers being of substantially rectangular cross section and each having its lower portion materially reduced in width relative to its upper portion, the inner side wall of the reduced lower portion of each hopper being substantially in the plane of the inner side wall of the upper portion and the outer side wall of the reduced lower portion being connected to the outer side wall of the upper portion by a downwardly and inwardly inclined wall, closure gates pivoted on the lower ends of said hoppers at the rear thereof, latch means effective for positively holding said gates closed, means for releasing said latch means and thereby releasing said gates for opening as said carriages reach discharging position, and means for limiting the extent of opening of said gates and returning them to closed position.

7. In a batching machine for delivering fine and coarse aggregates separately and in measured quantities to a skip of a concrete mixer, a supporting frame, a two compartment bin structure on said frame provided at its lower end with two juxtaposed discharge necks respectively opening downward from said compartments, two parallel carriages mounted on said frame respectively underlying said necks and movable transversely of said frame to an outer discharging position projecting beyond said frame and an inner charging position, batching hoppers depending from
